UNITED STATES PATENT OFFICE

HERMAN J. DE LANO, OF ALLEGAN, MICHIGAN, ASSIGNOR TO DE LANO SERVICE, OF ALLEGAN, MICHIGAN

DEPOSIT RECORD

Application filed March 24, 1930. Serial No. 438,326.

The main objects of this invention are to provide a deposit or accounting record such as the so-called "Christmas Club" savings accounts which greatly facilitates the keeping 5 of the record, minimizes mistakes, and also an account which may be easily checked.

Objects relating to details and economies of my invention will appear from the description to follow. The invention is defined and pointed out in the claims.

A structure which is a preferred embodiment of my invention is illustrated in the accompanying drawing, in which:

Fig. 1 is a face view of one of a coacting pair of sheets constituting my improved account record.

Fig. 2 is a face view of the other sheet, a portion only of the printed matter of the sheets being shown.

Fig. 3 is a perspective view illustrating the arrangement of sheets while the record is being made thereon, one position of the sheets being indicated by full lines and another by dotted lines.

Referring to the drawing, a pair of sheets 25 1 and 2 constitute or relate to a single record, these sheets having corresponding numbers, as the numbers 108 shown in the drawing, the numbers being preferably arranged 30 at the top of the sheets.

The sheet 2 is shorter than the sheet 1 so that when the sheet 1 is arranged in the superimposed relation to the sheet 2, the name spaces 3 of both sheets are exposed, as shown 35 in Fig. 3.

The sheet 2 is designed for office or bank record while the sheet 1 is the customer's receipt or record. The office record has address space thereon. The record shown is 40 made up for a \$10.00 payment record.

Each record has date-due spaces 4, amount-due spaces 5 and total-paid spaces 6 arranged in parallel sets, the sets being divided by the vertical central rulings 7. These columns are 45 filled out; that is, the amount due, the date due and the total paid are printed. The sheets also have date-paid columns 8 for each sheet, each column covering a period of twenty-five weeks.

The date-paid column of sheet 2 is arranged

adjacent the center ruling 7 thereof while the date-paid column of sheet 1 is arranged at the outer edge thereof.

With this arrangement, the customer's sheet 1 may be superimposed upon the office 55 sheet 2 with one of its edges registering with the center ruling or line 7 thereof which brings the date-paid column of the customer's sheet into alignment with one of the date-paid columns of the office record so that 60 the dates can be readily filled in as by use of a double dating stamp 9 which insures accuracy as well as saving time. Even where the dates are filled in by hand, the positioning of the sheets in this way greatly facilitates the making of records. 65

Further, when the sheet 1 is superimposed upon the sheet 2 as shown in Fig. 3, for example, the name of the customer on both sheets is exposed as well as the number of the accounts so that further checking may be 70 had against error.

I have illustrated my improvements as embodied in a Christmas savings club record but it will be understood by those skilled in 75 the art that it is desirable for use and readily adapted to other types of accounts where accuracy and speed is desired; for instance, school savings accounts and the like in which case the amounts would ordinarily be filled 80 in as the records are made.

Having thus described my invention, what I claim as new and desire to secure by Letters Patent, is:

1. A record device comprising a pair of 85 record sheets each having a designated name space and corresponding number at the top, one sheet being shorter than the other so that when the shorter sheet is superimposed upon the longer, the name in the name spaces and numbers of both sheets are exposed for comparison, both sheets having a longitudinal center ruling and both having filled in designated amount-due, total-paid, and date-due 90 columns and blank date-paid columns at each side of their center rulings, the date-paid columns of the longer sheet being arranged adjacent its center ruling and the blank date-paid columns of the shorter sheet being arranged at its side edges so that the sheets 95 100

may be arranged to juxtapose corresponding date-paid spaces of the sheets, thereby facilitating the entry of dates in the corresponding date spaces and permitting their simultaneous entry as by means of a double dating device.

2. A record device comprising a pair of record sheets each having a designated name space and corresponding number at the top, one sheet being shorter than the other so that when the shorter sheet is superimposed upon the longer, the names in the name spaces and the numbers are both exposed for comparison, both sheets having parallel sets of designated amount-due, total-paid, date-due and date-paid columns, the date-paid columns of the longer sheet being arranged side by side at the center of the sheet and the date-paid columns of the shorter sheet being arranged at the side edges thereof so that the sheets may be superimposed to juxtapose the corresponding date-paid spaces of the two sheets, thereby facilitating the entry of dates in the corresponding date spaces and permitting their simultaneous entry as by means of a double dating device.

3. A record device comprising a pair of record sheets each having a designated name space and corresponding number at the top, one sheet being shorter than the other so that when the shorter sheet is superimposed upon the longer, the name in the name spaces and the numbers are both exposed for comparison, both sheets having corresponding sets of data and blank date spaces transversely aligned therewith, the date-paid columns of the longer sheet being arranged side by side at the center of the sheet and the blank date spaces of the other sheet being arranged at the side edges thereof so that the sheets may be superimposed to juxtapose the corresponding blank date spaces of the two sheets, thereby facilitating the entry of dates in the corresponding date spaces.

45 In witness whereof I have hereunto set my hand.

HERMAN J. DE LANO.
